COIN CONTROLLED DOORBELL DEVICE

Murray P. Torrance, Lakewood, Ohio

Application September 22, 1937, Serial No. 165,159

4 Claims. (Cl. 194—8)

My invention relates to improvements in doorbell systems, and more particularly to coin controlled doorbell systems of the type requiring the caller to deposit a coin before ringing of the bell can be effected.

I am well aware of the fact that numerous devices have heretofore been made to control doorbell systems by coins for the purpose of reducing to a minimum the ringing of door bells, by undesirable or unwanted callers, but all of such prior devices, to the best of my knowledge, have been highly complicated structures; costly to manufacture; and extremely difficult to install, thus requiring skilled labor.

Another objection to doorbell systems of this type in the past, has been that to install them, it was necessary to cut into the door or door framing, or in some cases both, which in addition to being costly from a point of installation defaced the door and door-frame, in the event it became desirable to remove the system at some time later.

Therefore, an object of the present invention is to provide an improved coin controlled doorbell system, the construction of which is extremely simple, and which can be economically manufactured and marketed at a comparatively low cost.

Another object of the invention, is to provide a coin controlled, self-contained unit, which can be easily and quickly interchanged for the conventional doorbell button, without requiring skilled labor, and without defacing the door or the door-frame, to which it is attached.

Other objects and features of the invention will become apparent from the following description, relating to the accompanying drawing, which show the preferred form. The essential characteristics are summarized in the claims.

Referring now to the drawing, wherein like reference characters represent corresponding parts throughout the several views, and in which: Fig. 1 is a front elevation of a coin controlled doorbell made in accordance with the present invention; Fig. 2 is a similar view with the outer stamped case removed to clearly show the base and associated parts and with a coin inserted and partially broken away to expose one terminal of the coin controlled bell circuit; Fig. 3 is a vertical longitudinal section taken on a plane corresponding to line 3—3 of Fig. 1, and looking in the direction indicated by the arrowheads; Fig. 4 is a cross sectional view of the parts shown in Fig. 1 on offset planes indicated by the line 4—4 on Fig. 1; Fig. 5 is a cross section of Fig. 1

as indicated, for example, by the lines 5—5 on Fig. 1; Fig. 6 is a fragmentary front elevation, partly broken away, and partly shown in section to illustrate a modification of the coin chute, and chute door, and; Fig. 7 illustrates a schematic view of the wiring diagram for the system.

Referring now to the drawing for a detailed description of the present invention, and for the moment to Fig. 1, the reference numeral 10 designates as a whole, my improved self-contained 10 coin controlled doorbell unit, which may be easily and quickly interchanged for the conventional doorbell button.

The principal parts of this unit comprise the 15 base 11 and the case 12. In the preferred arrangement base 11 is made from any non-conductive material, such for example, as wood, hard rubber, plastics, glass, or if desired, from metal which is suitably electrically insulated. As best shown in Fig. 2, the base 11 is preferably 20 rectangular in shape and its marginal edges may be beveled as shown; the base 11 is further provided with a tortuous open recess, hereinafter referred to as the coin chute 13. The upper end 25 of this chute terminates near the left hand end of the beveled edge 14, and the lower end terminates near the lower end of the beveled edge 15, as clearly shown in Fig. 2. The width of the chute 13, is slightly greater than the diameter 30 of the coin intended for use in operating the system, so that the coin, when inserted in the chute, will drop under the influence of gravity. The outer wall of chute 13 is formed by case 12, when the latter is mounted over the base as best seen 35 in Fig. 5. The base 11 supports terminals 16 and 17 of the bell circuit, hereinafter referred to, and the head of terminal 16 protrudes slightly into the coin chute 13, as clearly shown in Figs. 2 and 4. Terminal 17 is positioned on one side 40 of the chute, and serves to anchor one end of a flexible metallic strip 18 to the base. The anchored end of strip 18 is preferably recessed into the base as clearly illustrated in Fig. 4 so as not to interfere, or come into contact with, the case 12. The free end of the flexible metallic strip 18 extends nearly across the chute 13, and out of alignment with terminal 16 and is bent slightly away from the base to permit a coin to pass readily between it and said terminal. 45

In order to complete the doorbell circuit, it is 50 necessary to bridge the strip 18 with terminal 16, and this is accomplished in the present invention, by stopping the inserted coin at a point within the chute, between the strip 18 and terminal 16. Means for stopping a coin C in the 55

position shown in Fig. 2 may comprise a bar 19, slidably received by slots 20-20 in base 11 (Fig. 3) and normally urged to coin stopping position by spring 21 encircling said bar, and received by a large recess 22 in base 11. The outer end of bar 19 protrudes beyond the base, and has attached thereto, in any suitable manner, a knob or finger piece 23, by which the bar can be manually withdrawn against the tension of spring 21 to permit the coin C to drop to the lower extremity of chute 13 where it is stopped by chute door 24.

The case may be stamped from sheet metal, and shaped to conform to the base. In such form, it has beveled sides, the angle of which corresponds to the beveled sides of the base, while slots 25 and 26 are provided in two of such sides, and in a position to register with the upper and lower ends, respectively, of chute 13. The chute door 24 is hinged to the case 12, as at 27, and in a position to cover the slot 26, and is normally held closed over said slot as by spring 28. The free end of the door terminates in a finger piece 29 which extends beyond the face of the beveled side 30 of case 12, in a manner permitting it to be grasped for the purpose of opening the door against the tension of spring 28, when removing the coin from the chute.

Referring now to the wiring diagram, illustrated in Fig. 7, the conductors 31-31 represent service lines supplying the customary 110 volts to the primary P of a conventional transformer T. Conductor 32 connects one terminal of bell B with one terminal of the secondary S of transformer T, and conductor 33 connects the other terminal of bell B with terminal 17. Terminal 16 is connected with the remaining terminal of the secondary S of the transformer T as by electrical conductor 33. It will become apparent that when a caller inserts a coin through slot 25 in case 12, and allows it to drop within the chute 13, it will be stopped in said chute by bar 19 and interposed between the strip 18 and terminal 16, as indicated in Figs. 1 and 2.

With the coin C in this position, it is only necessary to press the strip 18 against the coin C and the coin in turn against that portion of terminal 16, which protrudes into the chute 13, to close the electrical circuit for bell B. To this end I provide a push-button, 35, preferably of non-conductive material and having a flange 36 formed integral therewith. The reduced portion 35 of said button is slidably received by an opening in the case 12, and the diameter of this opening is smaller than the diameter of the flange, as clearly illustrated in Fig. 4 to prevent removal of the button. The case 12, may be dished out in the region of the push-button, if desired, to allow sufficient space for a coin to drop between the strip 18 and the terminal 16 without closing the bell circuit, until the button 35 is pressed inwardly.

When assembling my novel coin controlled bell button unit, the first step is to attach the conductors 33-34 to terminals 16 and 17 respectively, as for example, by nuts 37 threaded to the terminals as shown in Fig. 4. If desired, recesses 39 may be supplied in the base member to receive the nuts 37 and in this way keep the rear surface of the base flat so that it can be mounted upon any smooth surface as for example, a door or door-frame. After the conductors 33-34 are attached to the terminals 16 and 17 and the push-button 35 inserted in the opening in case 12, the case is fitted over the base and the entire unit

mounted in the desired location as by screw 38, passing through the case and base.

In Fig. 6, I have shown a modified base and case, and, as here shown, the coin chute 13a terminates at the bottom rather than at the side of the case, and the chute door 24a is shown hinged at 27a and provided with a spring clip 28a, which is adapted to snap past an obstruction 28b formed in the chute 13a. In this manner the chute door is held in a closed position, when snapped shut. The chute door 24a is also provided with a finger piece 29a which extends outwardly beyond the case so as to be readily grasped by a caller when it is desired to open the chute door 24a for the purpose of retrieving his coin. It will be noted that in this construction, the beveled side walls of the base and case are eliminated.

It will be readily apparent from the foregoing description, taken in connection with the accompanying drawing, that I have invented an extremely simple coin controlled door bell system, which can be inexpensively manufactured and sold and which can be installed by unskilled labor; which is extremely compact in design; and which can be readily and quickly interchanged for the conventional door bell push-button.

While I have herein disclosed specific applications of my invention, it will be understood that it is capable of application in other modifications and arrangements, which will be apparent to those skilled in this art, and I desire to include such within the scope and meaning of the appended claims.

I claim:

1. A coin controlled push-button unit for electrical doorbell systems comprising in combination, a base of non-conductive material having a coin chute therein, a case adapted to fit over the base to complete said chute, manually operable means adapted to intercept the chute including a sliding bar, resilient means to normally hold said bar in intercepting position within the chute, a pair of electrical terminals carried by the base, one of which is partially exposed within the chute, a spring member anchored to the other of said terminals and partially extending into the chute, and a push-button slidably carried by the case and adapted to be manually moved to cause a coin dropped in the chute and arrested by said bar to contact with one of said terminals and said spring member.

2. In a self-contained controlled push-button unit for electrical doorbell systems, the combination of an elongated base having beveled sides and made from non-conductive material, a tortuous coin chute formed in the base, a metal case fitted over the base and having a dished-out portion supplied with an opening, a pair of electrical conductors carried by the base, coin arresting means slidably mounted in the base and normally intercepting the chute, manually operable means for withdrawing the coin arresting means from within the chute when desired, a push-button carried by the case and projecting through the opening in the latter, and a coin chute door normally closing the lower end of said chute, the unit being characterized in that when a coin is dropped into said chute and arrested adjacent said terminals by said arresting means it can be moved to bridging position across said terminals upon depression of said push-button.

3. In an electrically operated annunciator system, a generally flat base having a channel-like shallow depression in its front face which extends

- in a generally vertical direction in the applied position of the base, a hollow casing fitting over the base in a manner to close the open side of the depression and provide a guiding chute for a coin or token, spaced conductor means on the base associated with the interior of the chute and adapted to be electrically bridged by a coin or a token of predetermined size in a manner to close an annunciator circuit when the coin or token is in a predetermined position in the chute, and releasable means accessible from outside the casing, and projecting into the chute to arrest a coin in such position.
4. A coin controlled push-button unit for electrical doorbell systems, comprising in combination a base in the form of a substantially flat slab

having a comparatively wide and shallow upright groove in its face, a cover adapted to fit over the base, the base and cover together providing by means of said groove a gravitational coin chute, a device operable from the exterior for interrupting said chute and supporting a coin dropped therein, a spring strip of metal secured to the base and extending across the chute in position to engage a coin of proper size adjacent the edge thereof, means for connecting one terminal to the spring strip and the other terminal to a contact adapted to be engaged by the coin, and a push-button supported by the cover and available for pressing said strip against the coin.
